MACHINE FOR OPERATING ON SOLE PARTS

Alfred F. Donovan, Boston, Mass., assignor to
 E. T. Wright & Co., Incorporated, Rockland,
 Mass., a corporation of Massachusetts

Application November 25, 1947, Serial No. 787,882

11 Claims. (Cl. 12—17)

1

This invention relates to the manufacture of footwear and more especially to apparatus useful in the preparation of an insole and a pad to facilitate the assemblage therewith of a shank-piece or stiffener in an improved shoe bottom structure of the type disclosed and claimed in United States Letters Patent No. 2,147,887, February 21, 1939 including an insole-proper, a metatarsal pad united to the under surface of the insole and a shank-piece or stiffener having its forward end overlapping the pad.

To insure that all the advantages obtainable by the use of such a pad and shank-piece are secured, it is essential, as pointed out in said patent, that the forward end of the shank-piece be accurately located relative to the pad. In said patent it was suggested that the pad be provided with a transverse slot or recess, and that the forward end of the shank-piece be provided with a flange and/or prongs to seat in said recess, thereby to facilitate the assemblage of the shank-piece and insole and to make sure that when so assembled they will be accurately related, assuming, of course, that the transverse slot in the pad has first been properly located.

The principal object of the present invention is to provide an apparatus for facilitating and insuring the accurate location and formation of such a transverse slot in the metatarsal pad regardless of the size, shape, or left or right contour of the insole thereby to insure precision and uniformity in the location of the shank-piece.

Other objects are to provide an apparatus of the character described which may be quickly and conveniently adapted to operate on left or right insoles without the removal or replacement of any parts, which affords to the operator a clear vision of the work during substantially the entire slotting operation, which in no way hinders or interferes with the withdrawal of the insole operated upon and the insertion of a new insole to be operated upon, and which eliminates all elements of guess work by the operator with respect to the proper positioning of the insole and pad, thereby to increase the speed of production while insuring uniformity and accuracy in the location of the transverse slot.

According to the present invention the apparatus comprises a support for the central portion of an insole, a holder having a slotting die relatively movable toward and away from said support so as to form a slot in the metatarsal pad of an insole disposed on said support, a positioning member mounted independently of the holder movable toward and away from said support and

2

yieldingly urged toward said support, said member having a part engageable with the rear edge portion of said pad so as to position and maintain said insole and pad in a predetermined position relative to the path of travel of said die, and means for effecting a relative movement between said holder and support. The positioning member is pivoted at one end independently of the holder and is yieldingly urged downwardly toward said support and has positioning fingers rockably mounted at the free end of the positioning member engageable with the rear edge portion of said pad.

In a more specific aspect of the invention that the means for positioning and maintaining an insole and pad in a predetermined position relative to the path of travel of said die comprises spaced parallel arms pivoted at one end inwardly of the support and independently of the holder, said arms extending outwardly over the support and straddling the path of travel of the slotting die and yieldingly urged downwardly toward the support, and positioning fingers rockably mounted intermediate the free ends of said arms and engageable with the rear edge portion of said pad, and means for holding the arms and positioning fingers in inoperative position out of contact with the support.

In another aspect of the invention the apparatus comprises a link pivotally mounted at one end and movable toward and away from said support and yieldingly urged toward said support, and an elongate positioning member having positioning fingers at its inner end engageable with the rear edge portion of said pad and having an upwardly curved tail portion at its outer end, the positioning member being rockably mounted adjacent its inner end to the free end of the link whereby when the insole is withdrawn the positioning fingers are rocked to a position to release the pad and when a new insole is inserted the positioning fingers are rocked back into position to determine the location of the new metatarsal pad and insole.

In still another aspect of the invention the support supports the central portions of right and left insoles, the holder and slotting die are rotatable relative to each other and means are provided for rotating said slotting die so as to operate on right and left insoles. The support is laterally movable.

In a still more specific aspect the holder comprises a rotatable die holder having an axial bore, a spindle within the axial bore fixed with relation to the rotational movement of the hold-

55

er, a transverse way at the lower end of the holder radially offset from the lower end of the spindle, a slotting die slidably mounted in said way, and crank means pivotally interconnecting the die with the spindle, means being provided for rotating the die holder so as to position the die to operate on right and left insoles.

For the purpose of illustration typical embodiments of the invention are shown in the accompanying drawings:

Fig. 1 is a front elevation of a typical embodiment of the invention;

Fig. 2 is a side elevation of the embodiment of Fig. 1;

Fig. 3 is an enlarged section along the line 3—3 of Fig. 1 with an insole and pad disposed on the support and with parts in elevation;

Fig. 4 is a fragmentary plan view of Fig. 3;

Fig. 5 is an enlarged section along the line 5—5 of Fig. 1;

Fig. 6 is a section along the line 6—6 of Fig. 5, showing the holder rotated to operate on a left insole;

Fig. 7 is a section along the line 6—6 of Fig. 5 showing the holder rotated to operate on a right insole;

Fig. 8 is a perspective view of the slotting die of the embodiment of Fig. 1;

Fig. 9 is a section similar to Fig. 5 showing a modified embodiment of the holder of the embodiment of Fig. 1;

Fig. 10 is a section of the modified embodiment of Fig. 9 shown in a position similar to Fig. 6;

Fig. 11 is a section of the modified embodiment of Fig. 9 shown in a position similar to Fig. 7;

Fig. 12 is a plan view showing the bottom of an insole as it appears after the slotting operation;

Fig. 13 is a perspective view of the shank piece showing the elements of the shank which cooperate with the slot in the metatarsal pad of Fig. 12 in the assembly of the parts.

Referring to the drawings, the numeral 1 designates the base of a punch press of well-known commercial type in which the present improvements are embodied, such press having a worktable 2 mounted on the base, an upstanding frame 3 carrying a drive shaft 5 to which a head carrier 4 is connected for reciprocating movement toward and away from the worktable along a vertical axis, the drive shaft being connected in turn to a drive wheel 6. The press is operated by power and controlled by a treadle or other suitable means (not shown) common to punch presses of this type.

In accordance with the present invention, the top surface of the worktable 2 is provided with front and rear guide members 7 and supports a mold-carrying block 8 slidable from side to side of the table between said guides. The block 8 is formed with spaced dovetailed channels 9 for slidably receiving dovetailed molds 10 and 11 the upper surfaces of which project above the block and are formed with depressions designed to receive the central portion of right and left molded insoles, respectively. End stops 12 and 13 for the guide-carrying block are mounted on the top surface of the table adjacent its opposite side edges and rearwardly of the rear edge of the block 8 by suitable means here shown as depending brackets 14 and 15 fixedly secured to the bottom surfaces of the end stops and the side edges of the worktable by screws 16. Inwardly

projecting latch members 17 and 18 are pivotally mounted on end stops 12 and 13, respectively, by pintles 19 and are respectively adapted to releasably engage lugs 20 and 21 projecting rearwardly from the rear edge of the block 8 adjacent its corners. That is, when the guide-carrying block 8 is slid to the left to bring the left mold 11 into the path of travel of the head carrier 4, as shown in Fig. 1, the latch member 17 releasably engages the lug 20, and when the block 8 is slid to the right to bring the right mold 10 into the path of travel of the head carrier, as shown in dot-and-dash lines in Fig. 1, the latch member 18 releasably engages the lug 21. To facilitate the sliding of the mold-carrying block 8, the opposite ends of the block are provided with handles 22.

A support and gauge 23 for the heel of the insole is substantially T-shaped in cross section and has the lower end of its leg 24 fixedly mounted to the front face of the table 2 intermediate the ends of the face by suitable means, as screws 25. The top surface of the head of the T is disposed in the plane of the top surface of the forward end of the molds 10 and 11 while the rear end of the head is juxtaposed to the front face of the mold-carrying block 8 and the front end of the head extends forwardly from the block as best shown in Fig. 2. The top surface of the forward end of the head is formed with a central longitudinally extending gauge line 26 (Fig. 1) which serves as a gauge with which to align the longitudinal center line of the heel portion of an insole disposed on the head of the T.

Adjacent the rear edge of the worktable 2 a pair of spaced upright posts 30 and 31 are mounted, as shown in Figs. 1 and 2, the posts being interconnected adjacent their top ends by a fixed rod 32. Spaced parallel link rods 36 and 37 are respectively secured at one end to sleeves 33 and 34 pivotally mounted on the fixed rod 32 and are locked in spaced relation lengthwise of the fixed rod 32 by suitable means here shown as collars 35 secured to the fixed rod 32 on opposite sides of sleeves 33 and 34. The link rods extend outwardly over the mold-carrying block 8 and in straddling relation to the path of travel of the head carrier 4. Depending arms 38 and 39 are respectively fixedly mounted to the opposite ends of the link rods 36 and 37 and are formed on their opposed faces adjacent their lower ends with recesses 27 and 28, constituting bearings, for pivotally receiving opposite ends of a pintle 40 extending therebetween.

An elongate positioning member 41 is fixedly secured centrally of the pintle 40 with its longitudinal axis in registry with the gauge line 26 of the support 23. One end of the positioning member 41 extends rearwardly and is formed with forked positioning fingers 42 and 43, as shown in Fig. 4, said fingers being adapted to engage the rear edges of the metatarsal pad of an insole as will hereinafter be more specifically described. The opposite end of the positioning member 41 extends forwardly over the rear end of the head of the T-shaped support and is formed with an upwardly curved tail 44, as shown in Figs. 2 and 3.

A cylindrical head 46 for rotatably holding a slotting die 52 is rotatably mounted at the lower end of the head carrier 4 and is carried toward and away from the worktable 2 and molds 10 and 11 by the reciprocating movement of the head carrier. Referring to Fig. 5, the head may be formed with an axial bore 47 for receiving a

spindle 48 projecting downwardly from the head carrier 4 and fixed with relation to the rotatable movement of the head. At its lower end the spindle is formed with a crank arm 49 extending transversely of and forwardly of the head into a recess 50 formed in the head adjacent its lower end. A front plate 53 is removably secured in a recess 54, also provided adjacent the lower end of the head, by a screw 55 and is formed at its rear face adjacent its lower end with a projecting key 56. Below the crank arm 49 a block 57 is similarly removably secured to the head 46 by a screw 58. The slotting die 52 is slidably mounted within the transverse way formed between the rear face of the front plate 53 and the front face of the block 57, the key 56 being slidably received in a channel 60 formed in the side edge of the slotting die, and the end of the crank being pivotally received, in turn, in a recess 51 formed in the top edge of the slotting die.

From the foregoing it will be evident that even though the slotting die is radially and forwardly offset from the axial bore of the head when, by movement of a handle 61 which is mounted on the head 46 and provided with a spring-actuated latch 66, the head is rotated to the right to a predetermined position for operating on right insoles, the slotting die will rotate to the position shown in Fig. 7 and will also slide in the transverse way to the left to compensate for any eccentricity between the slotting die and the axial bore. In a similar manner, when the head is rotated to the left to a predetermined position for operating on left insoles, the slotting die will rotate to the position shown in Fig. 6 and will also slide in the transverse way to the right to compensate for any eccentricity between the slotting die and the axial bore. By this means the slotting die may be mounted forwardly of the axial bore of the head and in combination with the oblique lower outer corner 62 formed in the front plate 53 will provide the operator at all times with a clear vision of the operating environment of the slotting die.

The slotting die 52 has a flat-bottomed surface formed with a downwardly projecting indenting blade 63 extending longitudinally of the die adjacent its forward edge and the blade is also formed with a pair of projections or teeth 64 and 65 spaced apart and in the plane of the blade proper.

In an alternative construction and with reference to Fig. 9 in which corresponding elements are indicated by similar reference numerals, the crank arm of the spindle has been omitted, as well as the block 57, while the front plate 53 is L-shaped in cross section, the key 56 being formed at the rear edge of the base of the L. The blade 63 of the slotting die is disposed centrally of the front and rear longitudinal edges of the die and the slotting die is mounted between the rear edge of the base of the L and the front face of the head adjacent its lower end, the key 56 being received in the channel 60 and the lower end of the spindle 48 being pivotally received in turn in the recess 51 at the top edge of the slotting die. From the foregoing it is evident that in the alternative construction the slotting die and blade are coaxial with the axial bore of the head, thereby eliminating any eccentricity between the slotting die and the axial bore and also eliminating the necessity of mounting the slotting die for sliding movement transversely of the head. That is, the

slotting die is positioned as shown in Fig. 11 when the head is rotated to the right to a predetermined position for operating on right insoles and is positioned as shown in Fig. 10 when the head is rotated to the left to a predetermined position for operating on left insoles. To enhance the vision of the operator when the slotting die is thus coaxially disposed in the head, the lower outer corner 62 of the front plate 53 is more deeply cut away, as shown in Fig. 9.

As shown in Fig. 1, a bracket 67 is mounted at the front of the carrier 4 adjacent its lower end by suitable means, as screws 68, the bracket being formed with a lateral slot 69 the edges defining the slot being adapted to receive and releasably engage the tail of the positioning member 41 when swung to an inoperative elevated position as shown in the upper dot-and-dash lines of Fig. 2.

An insole 70 which is to be operated upon is here disclosed in Figs. 12 and 3 as a composite right insole consisting of a body member of leather or other suitable material having on its underside at its forepart an upstanding rib 81, and a molded depression 71 at its ball portion for accommodating a metatarsal pad 72, the rear edges of the pad converging rearwardly to form an apex 73. The pad is held in predetermined position within the depression by a layer of fabric 74 cemented at its ends to the under surface of the insole by suitable means as adhesive cement, and extends across the under surface of the pad.

The shank piece 59 (Fig. 13), which is more fully described in the above-referred-to patent, is provided at its forward end with a slightly downwardly bent edge 75 and preferably with a pair of spaced prongs 76 and 77, the slightly downwardly bent edge being designed to seat within the transverse slot 78 (Fig. 12) formed in the metatarsal pad by the blade 63 as will be hereinafter described, while the prongs 76 and 77, respectively, enter the deeper portions or sockets 79 and 80 formed in the metatarsal pad 72 by the teeth 64 and 65, as will also be hereinafter described.

In using the apparatus described and assuming by way of example that right insoles of the type shown in Fig. 12 are to be operated upon, that the head is in retracted position as shown in Figs. 1 and 2, and that the positioning member 41 and link rods are in the elevated and inoperative position shown in the upper dot and dash lines in Fig. 2, the operator slides the mold-carrying block 8 to the right to bring the right mold 10 into the path of travel of the head carrier 4 as shown in dot and dash lines in Fig. 1 where it is releasably held in position by latch member 18 engaging the lug 21. The tail 44 of the positioning member 41 is then slipped out of engagement with the edges defining the slot 69 causing the positioning member 41 to drop by gravity into contact with the top surface of the mold 10 and into the substantially vertical position shown in the lower dot and dash lines in Fig. 2, the link rods and sleeves pivoting about the fixed rod 32.

The operator then rotates handle 61 of the head 46 away from him to the predetermined position for operating on right insoles which causes the slotting die to rotate to the position shown in Fig. 7. A right insole is now placed on the T-shaped support with the toe of the insole facing inwardly toward the machine and is pushed inwardly until the toe engages the ends of position-

ing fingers 42 and 43 which are in contact with the top surface of mold 10. Further inward movement of the insole causes the positioning member 41 and pintle 40 to rock within bearings 38 and 39 and to fall by gravity into a substantially horizontal position upon the under side of the insole. The insole is then moved further inwardly over the mold until the rear edges of the metatarsal pad slide beyond the ends of positioning fingers 42 and 43 after which the insole is pulled backwardly until the positioning fingers engage the rear edges of the pad, the apex of the pad entering into the space between the forked fingers as shown in Fig. 3 and the depression 71 of the insole lying in the depression of the mold 10. The center line of the heel portion of the insole is also aligned with the gauge line 28.

From the foregoing it is evident that irrespective of the size of the insole to be operated upon the metatarsal pad has been very accurately positioned with reference to the path of movement of the slotting die 52.

Having thus positioned the insole the punch press is now actuated causing the head carrier, the head and slotting die to advance with substantial pressure downwardly between the straddling link rods 36 and 37 upon the metatarsal pad, thus causing the blade 63 to indent the pad and thereby to form the groove or slot 78 while the teeth 64 and 65 of the blade concomitantly form the sockets 79 and 80 respectively. At the same time the flat under surface of the die tends to press the pad downwardly within the depression of the insole squeezing out any included bubbles of air between the pad and the insole so that the pad is compacted and caused to adhere strongly to the body member of the insole, it being understood that in the prior assembly of the parts adhesive is interposed between the insole proper and the pad.

At the completion of this slotting and compressing operation, the head carrier, head and die retract and the operator withdraws the insole with an outward and upward pull causing the tail of the positioning member to lift upwardly which, together with the outward pressure upon the ends of the positioning fingers still in engagement with the rear edges of the metatarsal pad, causes the positioning member and pintle 40 to rock back to the substantially vertical position, shown in the lower dot and dash lines in Fig. 2. Further, withdrawal of the insole causes the ends of the positioning fingers to trip upwardly over the rear edges of the pad and out of engagement therewith thereby to release the insole for complete withdrawal, the link rods and sleeves pivoting slightly about the fixed rod 32 to permit a slight upward movement of the positioning fingers. The upstanding rib 31 at the toe of the insole is cleared under the positioning fingers in the same manner on complete withdrawal of the insole. The operator then places a new right insole upon the T-shaped support and the cycle of operations above described is repeated. Should the positioning member fall by gravity to the horizontal position shown in Figs. 2 and 3, the upwardly curved tail 44 will facilitate the insertion of the new insole under the positioning member.

When it is desired to shift from the slotting of right insoles to left insoles the operator merely grasps the tail 44, lifts it to the elevated position shown in the upper dot and dash lines of Fig. 2 out of contact with the mold 10 and inserts the

end of the tail into the slot 69, the link rods and sleeves pivoting about the fixed rod 32 to permit the positioning member to be raised to such elevated position. The mold-carrying block 8 is slid to the left to bring the left mold 11 into the path of travel of the head carrier 4 as shown in Fig. 1 where it is releasably held in position by latch member 17 engaging the lug 29. The operator then rotates the handle of the head toward him to the predetermined position for operating on left insoles which causes the slotting die to rotate to the position shown in Fig. 6. The tail 44 is then slipped out of engagement with the edges defining the slot 69 to again cause the positioning member 41 to drop by gravity into contact with the top surface of the mold 11 and into the substantially vertical position shown in the lower dot and dash lines in Fig. 2. A left insole is then placed on the T-shaped support and the same cycle of operations above described in connection with operation on right insoles is repeated.

From the foregoing it is apparent that irrespective of the left or right contour of the insole the metatarsal pad is very accurately positioned with reference to the path of movement of the slotting die 52 for insuring an accurate location and formation of the transverse slot and that the apparatus described may be quickly adapted to operate on left or right insoles without the removal or replacement of any parts.

It should be understood that the present disclosure is for the purpose of illustration only and that this invention includes all modifications and equivalents which fall within the scope of the appended claims.

I claim:

1. Apparatus for use in slotting the metatarsal pad of an insole preparatory to assembly of a shank stiffener therewith, said apparatus comprising a support for the central portion of an insole, a holder having a slotting die relatively movable toward and away from said support so as to form a slot in the metatarsal pad of an insole disposed on said support, a positioning member mounted independently of the holder to move toward and away from said support, said member having a part engageable with the rear edge portion of said pad so as to position and maintain said insole and pad in a predetermined position relative to the path of travel of said die, and means for effecting a relative movement between said holder and support.

2. Apparatus for use in slotting the metatarsal pad of an insole preparatory to assembly of a shank stiffener therewith, said apparatus comprising a support for the central portion of an insole, a holder having a slotting die relatively movable toward and away from said support so as to form a slot in the metatarsal pad of an insole disposed on said support, means for positioning and maintaining the insole and pad in a predetermined position relative to the path of travel of said die, said means comprising a member pivoted at one end independently of the holder to move downwardly toward and upwardly away from said support and positioning fingers rockably mounted at the free end of the member adapted normally to rest on the insole disposed on said support and engageable with the rear edge portion of said pad, and means for effecting a relative movement between said holder and support.

3. Apparatus for use in slotting the metatarsal pad of an insole preparatory to assembly of a shank stiffener therewith, said apparatus com-

prising a support for the central portion of an insole, a holder having a slotting die relatively movable toward and away from said support so as to form a slot in the metatarsal pad of an insole disposed on said support, means for positioning and maintaining the insole and pad in a predetermined position relative to the path of travel of said die, said means comprising spaced parallel arms pivoted at one end inwardly of the support and independently of the holder to move toward and away from said support, said arms extending outwardly over the support and straddling the path of travel of the slotting die, and positioning fingers rockably mounted intermediate the free ends of said arms and engageable with the rear edge portion of said pad, means for effecting a relative movement between said holder and support, and means for holding the arms and positioning fingers in inoperative position out of contact with the support.

4. Apparatus for use in slotting the metatarsal pad of an insole preparatory to assembly of a shank stiffener therewith, said apparatus comprising a support for the central portion of an insole, a holder having a slotting die relatively movable toward and away from said support so as to form a slot in the metatarsal pad of an insole disposed on said support, a link pivotally mounted at one end to move toward and away from said support, and an elongate positioning member having positioning fingers at its inner end engageable with the rear edge portion of said pad so as to position and maintain said insole and pad in a predetermined position relative to the path of travel of said die and having an upwardly curved tail portion at its outer end, and means for effecting a relative movement between said holder and support, the positioning member being rockably mounted adjacent its inner end to the free end of the link, whereby when the insole is withdrawn the positioning fingers are rocked to a position to release the pad and when a new insole is inserted the positioning fingers are rocked back into position to determine the location of the new metatarsal pad and insole.

5. Apparatus for use in slotting the metatarsal pad of an insole preparatory to assembly of a shank stiffener therewith, said apparatus comprising a support for the central portion of right and left insoles, a holder and slotting die rotatable relative to each other and relatively movable toward and away from said support so as to form a slot in a metatarsal pad of an insole disposed on said support, means for rotating said slotting die so as to operate on right and left insoles, a positioning member mounted to move toward and away from said support, said member having a part engageable with the rear edge portion of said pad so as to position and maintain said insole and pad in a predetermined relation to the path of travel of said die, and means for effecting a relative movement between said holder and support.

6. Apparatus for use in slotting the metatarsal pad of an insole preparatory to assembly of a shank stiffener therewith, said apparatus comprising a support for the central portion of right and left insoles, a holder and slotting die rotatable relative to each other and relatively movable toward and away from said support so as to form a slot in a metatarsal pad of an insole disposed on said support, means for rotating said slotting die so as to operate on right and left insoles, a positioning member mounted independently of the holder to move toward and away

from said support, said member having a part engageable with the rear edge portion of said pad so as to position and maintain said insole and pad in a predetermined position relative to the path of travel of said die, and means for effecting a relative movement between said holder and support.

7. Apparatus for use in slotting the metatarsal pad of an insole preparatory to assembly of a shank stiffener therewith, said apparatus comprising a support for the central portion of right and left insoles, a holder and slotting die rotatable relative to each other and relatively movable toward and away from said support so as to form a slot in a metatarsal pad of an insole disposed on said support, means for rotating said slotting die so as to operate on right and left insoles, means for positioning and maintaining the insole and pad in a predetermined position relative to the path of travel of said die, said means comprising a member pivoted at one end independently of the holder to move downwardly towards and upwardly away from said support and having fingers rockably mounted at the free end of the member adapted normally to rest on the insole disposed on said support and engageable with the rear edge portion of said pad.

8. Apparatus for use in slotting the metatarsal pad of an insole preparatory to assembly of a shank stiffener therewith, said apparatus comprising a support for the central portion of right and left insoles, a holder and slotting die rotatable relative to each other and relatively movable toward and away from said support so as to form a slot in a metatarsal pad of an insole disposed on said support, means for rotating said slotting die so as to operate on right and left insoles, means for positioning and maintaining the insole and pad in a predetermined position relative to the path of travel of said die, said means comprising spaced parallel arms pivoted at one end inwardly of the support and independently of the holder to move toward and away from said support, said arms extending outwardly over the support and straddling the path of travel of the slotting die, positioning fingers rockably mounted intermediate the free ends of said arms and engageable with the rear edge portion of said pad, means for effecting a relative movement between said holder and support, and means for holding the arms and positioning fingers in inoperative position out of contact with the support.

9. Apparatus for use in slotting the metatarsal pad of an insole preparatory to assembly of a shank stiffener therewith, said apparatus comprising a support for the central portion of right and left insoles, a holder and slotting die rotatable relative to each other and relatively movable toward and away from said support so as to form a slot in a metatarsal pad of an insole disposed on said support, means for rotating said slotting die so as to operate on right and left insoles, a link pivotally mounted at one end to move toward and away from said support, and an elongate positioning member having positioning fingers at its inner end engageable with the rear edge portion of said pad so as to position and maintain said insole and pad in a predetermined position relative to the path of travel of said die and having an upwardly curved tail portion at its outer end, and means for effecting a relative movement between said holder and support, the positioning member being rockably

mounted adjacent its inner end to the free end of the link, whereby when the insole is withdrawn the positioning fingers are rocked to a position to release the pad and when a new insole is inserted the positioning fingers are rocked back into position to determine the location of the new insole and pad.

10. Apparatus for use in slotting the metatarsal pad of an insole preparatory to assembly of a shank stiffener therewith, said apparatus comprising a laterally movable support for supporting the central portions of right and left insoles, a holder and slotting die rotatable relative to each other and relatively movable toward and away from said support so as to form a slot in the metatarsal pad of an insole disposed on said support, means for rotating said slotting die so as to operate on right and left insoles, a positioning member mounted for movement downwardly toward and upwardly away from said support, said member having a part engageable with the rear edge portion of said pad so as to position and maintain said insole and pad in a predetermined position relative to the path of travel of said die, and means for effecting a relative movement between said holder and support.

11. Apparatus for use in slotting the metatarsal

10

15

20

25

pad of an insole preparatory to assembly of a shank stiffener therewith, said apparatus comprising a support for the central portion of right and left insoles, a rotatable die holder having an axial bore, a spindle within the axial bore fixed with relation to the rotational movement of the holder, a transverse way at the lower end of the holder radially offset from the lower end of the spindle, a slotting die slidably mounted in said way and crank means pivotally interconnecting the die with the spindle, the die holder being movable toward and away from said support so as to form a slot in the metatarsal pad of an insole disposed on said support, means for rotating the die holder so as to position the die to operate on right and left insoles, a positioning member mounted to move toward and away from said support, said positioning member having a part engageable with the rear edge portion of said pad so as to position and maintain said insole and pad in a predetermined relation to the path of travel of said die, and means for effecting a relative movement between said die holder and support.

ALFRED F. DONOVAN.
